UNITED STATES PATENT OFFICE.

CLIFTON E. SINGLETON, OF NEW YORK, N. Y.

CYCLE-STAND.

No. 863,327.

Specification of Letters Patent.

Patented Aug. 13, 1907.

Application filed March 6, 1907. Serial No. 360,940.

To all whom it may concern:

Be it known that I, CLIFTON E. SINGLETON, a citizen of the United States, residing at the borough of Brooklyn, in the city of New York and State of New York, 5 have invented certain new and useful Improvements in Cycle-Stands, of which the following is a specification.

My invention relates to that class of cycle stands which holds the cycle in an erect position by providing suitable rests for the ends of the rear axle; and my 10 improvements consist in the particulars hereinafter set forth.

In the drawings Figures 1 and 3 are respectively a side view and a front view of the stand, opened, and 15 with the hub of a cycle supported therein; and Figs. 2 and 4 are respectively a side view and a front view of the stand showing it closed together, the broken lines in Fig. 4 indicating the changed positions of the parts when the frame is sprung apart to admit the hub of 20 the wheel. In Fig. 1 the left hand leg A is partially broken away to show the connection of the loop and stay rod, and in Fig. 4 the loops are shown partially in section for the same purpose.

Similar letters of reference designate similar parts 25 in all the figures.

The legs A A are fastened in pairs to base stretchers B B, and are secured at their tops by pivots *a a* to the axle-holders or heads C C. Two pair of braces D D are attached by pivots *d d* to the legs A A, their upper 30 ends being connected by the pivot pins *e e* which slide in the slots *c c* in the lower ends of the heads C C.

The upper ends of the stay rods F F are passed through 35 holes in the heads C and are secured by nuts *f f*, beneath which are, preferably, washers *f' f'* which overlap the ends of the legs A A and grip the same firmly when the stand is opened. The lower ends of these stay rods F F pass into loops *b b* riveted to the base 40 stretcher B, and are adjustably secured therein by nuts *g g*.

Normally, when the stand is closed as in Figs. 2 and 45 4, these stay rods are slack and the nuts *g g* are some distance below the tops of the loops *b b*. In this position the composite sides of the stand will not be rigid, but can easily be sprung out, as indicated by the broken lines in Fig. 4, so as to allow the ends of the rear 50 axle to be slipped into the holes *C' C'* therein. But when the leg members are then spread apart, as shown in Fig. 1, the distance between the loops *b b* and the bearings of the upper ends of the rods F F in the heads C C will be lengthened, taking up the slack, and bringing 55 the nuts *g g* up under the tops of the loops *b b*, there-

by drawing the tops of the frame members in against the ends of the cycle hub and anchoring them securely against lateral displacement. Adjustment of the stay rods F F can be secured by the nuts *f f* and *g g*. 55

The toggle-jointed connection of the braces D D with the bottom of the heads C C serves to spread the legs equally, to each side of the heads, when they are opened, which is necessary to secure the proper operation of the device.

The greater the weight of the cycle the more securely will it be gripped in the stand, for the weight will keep the legs spread and effectually prevent the accidental folding up of the frame and slackening of the stay rods F F. This is particularly important when the stand is 65 used to support a motor cycle, for which purpose it is particularly designed; because, as is well known, it is customary to test the motor while the cycle is in the stand, and not infrequently to mount the cycle in testing it; and any accidental loosening of the cycle from 70 the stand at such a time would be apt to cause serious damage.

Having thus described my invention what I claim and desire to secure by Letters Patent of the United States is:—

1. In a cycle stand, the combination of a folding frame provided with a laterally movable axle-bearing, and means actuated by the opening of the frame to front and rear to clamp said axle-bearing against outward lateral movement.

2. In a cycle stand, the combination of a pair of frames 80 each embodying a base and axle-bearing spring-arms rigidly attached thereto and adapted by means of their elasticity to be sprung apart to admit a cycle axle between them and to retract themselves to grasp said axle, and means, actuated by the spreading apart of said frames, to clamp said spring-arms against outward movement.

3. In a cycle stand, the combination of a pair of folding, flexible side-members provided with axle-bearings, and releasable means actuated by the opening of said side members to front and back to hold said side frames against 85 outward lateral movement.

4. In a cycle stand, the combination of a pair of axle-bearing heads, a pair of flexible side-members pivoted thereto, a spreader medially connected with one of said axle-bearing heads and having its ends engaging with said side members for spreading said members equally to front and rear of said heads, and means for holding the same against outward lateral movement.

5. In a cycle stand, the combination of a pair of axle-bearing heads, a pair of flexible side-members pivoted thereto, a jointed spreader having an end engaging with each of said side members and medially in sliding connection with one of said axle-bearing heads for spreading said side members equally to either side of said heads, and means consisting of adjustable truss rods for holding the 100 same against outward movement.

6. In a cycle stand, the combination of a pair of axle-bearing heads, a pair of flexible side-members pivoted

thereto, a pair of truss rods having their lower ends slidably connected with the bottom of one of said side members and having their upper ends pivoted in said heads eccentrically relative to the pivotal points of said side members therein.

7. In a cycle stand, the combination of a pair of axle-bearing heads provided with slots in their lower ends, a pair of flexible side-members pivoted thereto, a pair of toggle-jointed, governing braces having their ends pivoted to said side-members and their centers pivoted in the slots

in said heads, a pair of loops upon the bottom of one of said side-members, a pair of truss rods each having its lower end adjustably held in one of said loops by a nut and having its upper end pivoted in said head eccentrically relative to the pivotal points of said side members therein. 15
